DETACHABLE BUTTON AND BUTTON FASTENING DEVICE

Julia Rubenstein, New York, N.Y.

Application February 23, 1955, Serial No. 490,037

1 Claim. (Cl. 24—103)

This invention relates to a detachable button and button fastening device which may be used either alone as a button or ornament or the like or which may be used as a fastening means for fastening buttons, ornaments and the like to garments. It constitutes an improvement over the invention which is disclosed and claimed in my co-pending patent applications, Serial No. 338,744, filed on February 25, 1953 and Serial No. 368,147, filed on July 15, 1953. The present application is a continuation-in-part of these co-pending patent applications.

The principal object of this invention is the provision of a button or button fastening device which may very readily be attached to and detached from an article of wearing apparel. An important feature of the invention is the mechanical movement of its locking pin. In my two co-pending patent applications the locking pin is mounted for pivotal movement between open and closed positions about an axis which is biased with respect to the plane of the body of said button or button fastening device. In the present device on the other hand, the pivotal movement of the locking pin is about an axis to which a radial line drawn from the center of the body of said button or button fastening device is normal. The locking pin itself is situated substantially along said radial line when it is in its closed position.

An important feature of this pivotal connection between the locking pin and the body of the button or button fastening device is the clearance which is provided to enable the locking pin to rock in addition to pivot in order to facilitate engagement and disengagement of its free end with its keeper. This rocking movement is about an axis which is perpendicular to the pivotal axis about which the locking pin pivots.

Another important feature of this invention is in relation to the construction of the locking pin. At one end the locking pin is provided with a head, which, in one case may be a rounded head and in another case a cross-bar which, with the shank of the locking pin, defines a T-shaped member. The body of the button or button fastening device is provided with a curled peripheral edge defining an annular tunnel and a radial slot is provided in said peripheral edge for the shank of the locking pin. The head of the pin is held captive within said tunnel behind said slot and the pin is thereby rendered free to pivot toward and away from its keeper which is situated in the curled peripheral edge diametrically opposite the slot. The length of the slot determines the range of pivotal movement of the locking pin. The clearances determine the extent of rocking movement of which the locking pin is capable.

When the head of the pin is rounded, say in the shape of a sphere, the pin is free not only to pivot into and out of closed and opened positions, and not only is it free to rock so as to facilitate locking or unlocking the pin, but it is also free to rotate about the axis of its shank immediately adjacent said rounded head. The rocking axis would be perpendicular to the pivotal axis and the axis of rotation would also be perpendicular to the piv-

2

otal axis. By the same token, the axis of rotation would be perpendicular to the rocking axis.

The main body of the locking pin intermediate its two ends is bowed in the form of a bail and its free end is pointed and bent laterally for ready engagement with the keeper. It is this laterally bent pointed end which, together with the rocking (and rotative) movement of the locking pin, enables said pin to engage said keeper without flexing to an undesirable extent.

10 An important feature of this invention is its simplicity of construction and assembly. It consists simply of two components, one being a stamped and formed cap and the other being a bent pin. The cap is readily stamped and formed by conventional stamping and forming means and the pin may readily be assembled therewith by simply inserting its head within the tunnel formed by its peripheral curled edge.

The cap may be made of sheet metal, such as sheet steel, properly plated or coated to protect against rust and to provide good appearance or it may be made of perforated sheet material or metal cloth, screening or the like. The appearance and structure would be precisely the same as in the case of ordinary sheet metal, save for the holes, perforations or interstices. These holes, perforations or interstices may be employed in connection with means for securing ornaments, beads or the like to the cap of the present device, as by tying or sewing said ornaments, beads or the like to said perforated or meshed material. If desired, such ornaments or beads may be cemented to the cap of the device herein claimed and it will be observed in the specification which follows that the cap is recessed to provide a pocket for such ornaments, beads or the like, but such recessed construction is not a critical part of this invention and the cap may be made without a recess for this purpose. Similarly, although the cap is shown in the drawing to be disc-shaped, this is purely illustrative and it may be made in other shapes as well, its central web may be omitted, if desired, leaving a cap of purely annular shape.

40 The invention is illustrated in the accompanying drawing in which:

Fig. 1 is a plan view of a button and button fastening device showing its locking pin in open position.

Fig. 2 is a section therethrough on the line 2—2 of Fig. 1.

45 Fig. 3 is a view similar to that of Fig. 1 showing the locking pin in closed position.

Fig. 4 is a fragmentary perspective view of the headed end of the locking pin, said end including a crossbar which serves as the head of said pin.

50 Fig. 5 is another fragmentary perspective view of the headed end of said locking pin, the head on said pin being substantially spherical in shape.

Fig. 6 is still another perspective fragmentary view of the headed end of the locking pin, showing a head formed of the pin itself bent laterally in both directions and providing laterally opposite portions corresponding to the ends of the crossbar shown in Fig. 4.

60 Referring now to the drawing, it will be observed that the button and button fastening device herein claimed comprises but two parts: A cap 10 and a locking pin 12. This is important because the cap not only serves as a pivotal support for said locking pin but it also serves as a closure which encloses and conceals both operative ends of the locking pin, namely, the pivotal end and the locking end. Consequently, there is no need to provide a cover for said cap which would serve as an enclosure to conceal these ends of the locking pin.

65 It will be seen that cap 10 is substantially circular in plan view and that it is provided with a disc-shaped platform 14 which occupies a central position therein. The peripheral edge of disc-shaped platform 14 is bent to

form an annular wall 16 which possesses the form of a truncated cone. The wide end of said cone-shaped wall 16 is then curled to form an annular tubular peripheral portion 18 which defines an inner annular tunnel 20 substantially circular in cross-section.

It will appear from the foregoing, that cap 10 is generally disc-shaped in over-all form with a curled peripheral edge which defines an internal annular tunnel. A slot 22 is formed in said curled periphery, radially of the cap and a second slot 24 is formed in said curled periphery diametrically opposite slot 22 and in substantial alignment therewith. Both slots render access to the tunnel possible.

A cut-out 26 is provided in the peripheral curled portion 18 and a slightly raised lip 28 is provided between said cut-out 26 and slot 24. It will shortly be observed that this lip is important in the locking and unlocking of the entire device.

Locking pin 12 has a head 30 formed thereon or connected thereto at one end. At its opposite end is a relatively sharp pointed portion 32 which projects laterally from the main body of said locking pin. Between head 30 and pointed end 32 is a bowed portion or bail 34 which constitutes the main body of the locking pin. It is this bail which locks the device herein claimed to a garment and it is to this bail that a button may be secured.

The head of the locking pin 30 comprises a crossbar which is either connected to or integral with the back end of bail 34. Said crossbar projects laterally outwardly from both sides of said bail and together with said bail defines a T-shaped member. It will be observed that slot 22 accommodates the back end of bail 34 and crossbar 30 is held captive within tunnel 20. Crossbar 30 now functions as a pivot or fulcrum within said tunnel whereby the locking pin is enabled to pivot about the longitudinal axis of said crossbar. Figs. 1 and 2 show the locking pin in open position and Fig. 3 shows it in closed position. It will be observed that end wall 36 of slot 22 serves as a stop to prevent pivotal movement of the locking pin in counter-clockwise direction beyond its position in Fig. 2.

Fig. 4 is a perspective view of the back end of the locking pin including crossbar 30 which serves as its head. Fig. 5 shows a modification of this construction in the form of a ball-shaped head 38 mounted at the back end of a bail 34a which is similar to bail 34 above mentioned. This ball-shaped head need not necessarily be perfectly spherical in shape. A rounded head would suffice for the purposes of this invention. Another variation is shown in Fig. 6 where a bail 34b, similar to bails 34 and 34a, is bent at its back end laterally outwardly to form a portion 40, a bight 42 being provided at the end of said lateral portion 40, a cross member 44 being formed at the end of said bight 42 and terminating in a second bight 46, and an end piece 48 being formed at the end of said second bight. End piece 48 and lateral portion 40 are in axial alignment with each other and they function in substantially the same manner as crossbar 30 above mentioned. In both cases, the head comprises a pair of laterally projecting portions which are axially aligned and to which the back end of the bail is normal.

It will be understood that the head of the pin, whether it be crossbar 30 or ball 38 or lateral members 40 and 48, is wider than slot 22 so that it cannot pull through. It will also be understood that there is substantial clearance between the head of the pin and the inside wall of tunnel 20 and there is also clearance between the bail itself and the side edges 50 and 52 of the slot so as to enable the pin to rock laterally as well as to pivot either forwardly or backwardly to the positions shown in Figs. 3 and 1.

When the locking pin is in locked position, its pointed end 32 is disposed within tunnel 20 and the forward end of its bail 34 projects into slot 24. It is clear, therefore,

that the curled peripheral portion 18 serves as the keeper for said pointed end of the pin, preventing said pin from pivoting from closed to open position.

Lip 28 engages the bend or crook of the locking pin which is formed between its bail portion 34 and its pointed end portion 32. This prevents the locking pin from rocking and disengaging its pointed end from its keeper. However, when it is desired to open the pin, said pin may be forced laterally past lip 28 so as to bring its pointed end 32 into registration or partial registration with cut-out 26. The pointed end of the pin is now free from the curled periphery 18 which serves as its keeper and the pin may now be pivoted into open position as shown in Figs. 1 and 2. To close the pin, the procedure is reversed and the pin is rocked laterally so as to bring its pointed end into cut-out 26 and said pointed end is then forced past lip 28 and into engagement with the curled periphery 18 on the opposite side of slot 24 from lip 28. The bail itself projects into said slot 24.

The foregoing is illustrative of preferred forms of this invention and it will be understood that these preferred forms may be modified and other forms may be provided within the broad spirit of the invention and the broad scope of the claim.

I claim:

A button fastening device, comprising a cap having an elevated centrally disposed platform portion of disc shape and a depressed curled peripheral portion concentric with said platform and defining an internal annular tunnel substantially circular in cross-section, there being a radial slot formed in said curled peripheral portion, a locking pin having a head disposed within said tunnel behind the peripheral portion defining said radial slot, said head being larger than the radial slot to prevent dislodgment of said head through said radial slot, the shank of the locking pin projecting through said radial slot and being pivotally movable longitudinally of said radial slot about an axis to which said radial slot is normal, the head of said pin functioning as the pivot for such movement, the clearance between the shank of the pin and the edges of the radial slot being sufficient to enable the pin to rock about an axis perpendicular to said pivotal axis across the top of said platform, and a keeper provided in the curled peripheral portion of said cap diametrically opposite said radial slot, the free end of said pin being bent laterally for engagement with said keeper, the shank of the pin between its said head and its said bent free end being bowed to form a bail adapted to engage a shank-type button, the head of the locking pin comprising a portion of the shank of said locking pin which is bent laterally to one side of the pin and then across to the opposite side and then back into alignment with the first laterally bent portion, the keeper comprising a portion of the curled peripheral portion of the cap, said keeper being adapted to engage the free end of the pin when said free end is moved into the tunnel within said curled peripheral portion, there being an opening being provided in said curled peripheral portion through which said free end of the pin is adapted to pass into said tunnel.
